UNITED STATES PATENT OFFICE.

GEORGE GOULD GOING, OF MIDDLETON, CONNECTICUT, ASSIGNOR TO REMINGTON-
NOISELESS TYPEWRITER CORPORATION, OF NEW YORK, N. Y., A CORPORATION OF
NEW YORK.

TYPEWRITING MACHINE.

Application filed March 14, 1925. Serial No. 15,475.

My invention relates to typewriting or like machines and more particularly to line spacing mechanism therefor.

Generally stated, the main objects of the invention are to produce a line spacing mechanism which is simple in construction, highly efficient in use, may be manufactured at comparatively small cost, is easy to assemble, and may be introduced into or detached 10 from the machine as a single unit.

To the above and other ends which will hereinafter appear, my invention consists in the features of construction, arrangements of parts, and combination of devices set forth 15 in the following description and particularly pointed out in the appended claims.

In the accompanying drawings, wherein like reference characters designate corresponding parts in the different views:

20 Figure 1 is a fragmentary top plan view showing the line spacing mechanism of my invention and some of the associated parts.

Figure 2 is an enlarged fragmentary detail fore-and-aft vertical sectional view of 25 the same taken on the line 2—2 of Fig. 1 and looking in the direction of the arrows at said line; the view showing the parts as they appear at the end of the line spacing operation.

30 Figure 3 is a corresponding sectional view of the same taken on the line 3—3 of Fig. 1 and looking in the direction of the arrows at said line.

Figure 4 is a detail fragmentary vertical 35 transverse sectional view of the same taken on the line 4—4 of Fig. 1 and looking in the direction of the arrows at said line.

Figure 5 is a view corresponding substantially to Fig. 2 except that the parts are 40 shown in normal position, and some of the parts are broken away.

The invention is shown applied in the present instance to a carriage of a No. 5 Remington-noiseless machine, only so much 45 of said machine being shown however as is necessary to illustrate my invention in its embodiment therein. Obviously the invention may be embodied in other makes of typewriting or like machines.

50 In the drawings, 1 indicates a cylindrical platen suitably mounted to travel with and turn in the usual bodily case shiftable carriage of said Remington-noiseless machine, one of the end plates 2 of which carriage is 55 shown in the drawings. A line spacing

wheel 3 is operatively connected to turn with the platen, as is a finger wheel 4. The means by which the line spacing wheel is operatively connected with the platen may comprise a clutch controlled by the finger wheel 4 as 60 disclosed in the application to Barney 743-199 filed Oct. 13, 1924. However, for the purpose of the present invention it may be supposed that the platen, line spacing wheel and finger wheel 4 are fixedly connected to 65 turn together.

It will be seen that in the present instance the line spacing wheel and the line spacing devices that co-act therewith are arranged outside of the left-hand end plate 70 2 of the carriage, and most of such devices are carried by a single bracket or support 5. This bracket is preferably made of sheet metal and is secured to the left-hand end plate 2 of the carriage by screws 6 and 7. 75 The construction is such that all of the line spacing mechanism, except the line spacing wheel 3 and its spring-pressed roller detent 8 are adapted to be introduced into place on or detached from the carriage with the 80 bracket 5 as a single unit, as will hereinafter more clearly appear.

A line spacing handle or lever 9 that may be made from sheet metal is mounted to turn from left to right, or in the direction of the 85 return movement of the carriage, around a vertical axis on a headed pivot screw 10. Said screw is received at its threaded end in a tapped opening in the bracket 5 and extends below said bracket to receive a lock-nut 11. The line spacing lever carries at its forward end an upright finger piece 12 and at the rear end a depending pin 13. This pin passes through a slot 13^a in the bracket and has one end of a contractile spring 14 connected thereto, the other end of said spring 90 being connected to a fixed pin 15 secured to the under side of the bracket 5. The power of this spring is exerted to return the line spacing lever and the parts connected therewith to normal position shown in Figs. 1, 3 and 5. The parts are limited in such return movement by the pin 13 co-acting with the right hand end wall of the slot 13^a as 95 shown in Fig. 1. Extending laterally to the 100 right from the lever 9 is a crank arm 16, best shown in Fig. 1. This arm carries an up-standing post 17 which is fixed to the arm and is cylindrical in cross section, for purposes which will presently appear. Extend-

ing through the arm 16 below the post 17, and preferably forming a part of the means by which the latter is secured in place, is a pin 18 that extends below the arm 16. This pin is received in a slot 19 in a sheet metal carrier or slide 20, said slot extending longitudinally fore-and-aft of the machine, or in the general direction of the travel of said pin, a short distance to provide a lost motion connection between the pin and slide, for purposes which will hereinafter appear. The slide 20 is supported on the upper side of the bracket 5 for substantially rectilinear movement fore-and-aft of the machine and constitutes a carrier for a line spacing pawl 21. The slide 20 is guided in its movements in part by a headed screw 22, the stem of which passes through a slot 23 that extends fore-and-aft in the slide, the screw being received at its threaded end in a tapped opening in the bracket 5. The lower end of this screw extends beneath the bracket where it receives a lock nut 24. That part of the slide 20 to which the arm 16 of the line spacing lever is operatively connected as described, is in the nature of an arm 20^a off-set to the right of the main body portion of the slide. This brings the point of lost motion connection 18—19 between the line spacing lever and slide, and also the post 17, in the line of the fore-and-aft operations of the line spacing pawl 21, the slide being guided in its movements by the pin and slot connections 18—19 and 22—23.

35 The line spacing pawl overlies the line spacing wheel 3 and is pivoted near one end at 25 to one side of an upstanding lug 26 formed on the arm 20^a of the slide 20. The pivot 25 may be in the nature of a headed screw threaded into a tapped opening in the lug 26 and co-acting at its free end portion with a lock nut 27 on the right-hand side of the lug. The heel of the pawl, above its pivot 25, is bored longitudinally of the pawl to receive a plunger or pin 28 normally held pressed against the post 17 by a coiled expansion spring 29 contained within the bored opening in which the pin 28 slides. The power of this spring is therefore exerted at all times to turn the engaging nose 21^a of the pawl down towards the teeth of the line spacing wheel. It is through the spring 29 that motion is transmitted from the line spacing handle to the line spacing pawl and the slide 20. Positive connection between said parts is not brought about until the pawl has been arrested at the last part of its throw, as will hereinafter appear. In the normal position of the parts the pawl 21 is pressed towards the wheel 3 by the spring 29, but engagement with the wheel is prevented by an adjustable line space regulating device or arm 30. This regulating device in the present instance is in the nature of a guard, guide or shield on which the line

spacing pawl normally rests and slides in its line spacing movement, the extent of such sliding movement of the pawl on the shield determining the extent of line spacing movement transmitted to the platen. This regulating device 30 is made of sheet metal and is pivoted at one end, at 31, to an upstanding lug or bracket arm 32 formed on the bracket 5. It will be seen that this regulating arm is substantially horizontally disposed and extends forwardly from its pivot above the bracket, and in a direction opposite from the direction that the line spacing pawl extends from its pivot and parallel therewith. The pawl has a laterally projecting pin 33 that overlies and rides on the upper inclined cam edge 34 of the regulating arm 30, as best shown in Fig. 5. The pin 33 is pressed down on the cam 34 of the regulating device by the spring 29 of the pawl throughout the stroke of the latter. Therefore, the adjustment of the regulating arm 30 around its pivot 31 determines at what point in the throw of the pawl it will engage a tooth of the line spacing wheel.

To obtain such an adjustment of the arm 30, and in order to hold it and its co-acting adjusting means against accidental displacement, I provide the following means. It will be seen that the arm 30 is connected to one end of a contractile spring 35, the other end of said spring being connected to an off-set ear on a hand-controlled adjusting member or arm 36. This arm is pivoted at its lower end on a headed pivot screw 37 threaded into a tapped opening in a depending arm 38 on the bracket 5, the left-hand threaded end of the pivot screw 37 co-acting with a lock nut 39. It will be seen that this arm 36 is upright and extends longitudinally at substantially right angles to the length of the arm 30. A pin 40 projects laterally from the right-hand side of the arm 36 and underlies the arm 30. This pin is adapted to be seated in any one of three locking recesses or notches 41, 42, or 43 in the bottom edge of the arm 30. It will be seen that these recesses are at different distances from the pivotal center of the member 30, and that the pin 40 is adapted to determine the elevation of said member at any one of three different positions, depending on which of the three notches 41, 42 and 43 the pin may be shifted to and seated in. This variation in the elevation of the member 30 determines the point in the throw of the pawl where it will engage a tooth of the line spacing wheel and determines whether each actuation of the handle 9 shall feed the wheel and platen the distance of one, two or three teeth of the wheel.

By reason of the interlocking engagement of the pin 40 in any one of the notches 41, 42 or 43, and the member 30 exerting a downward spring pressure substantially

against the dead center of the arm 36, the member 30 will act as a spring detent on said arm to hold it against accidental displacement from any one of the three line determining positions to which it may be adjusted by hand. At the same time the member 30 is held against accidental displacement from the position to which it is adjusted by the hand-controlled member 36.

10 Oppositely disposed depending walls 44 and 45 co-incident with the outer end walls of the terminal recesses 41 and 43 respectively, limit the extreme adjusting movements of the member 36 in opposite directions by co-15 acting with the pin 40 in such positions.

A suitable finger piece 46 may be formed on the upper end of the member 36 by bending the plate from which said member is formed outwardly. On the upper face of this finger piece 46 suitable indices as "1", "2" and "3" may be provided. The corresponding one of these indices registers with the pin 33 in accordance with the adjustment of the member 36 to provide 25 one, two or three teeth spacing.

The pivot 31 of the regulating device 30 is in the nature of a screw threaded into a tapped opening in the bracket arm 32. The outer end of this screw receives a lock nut 30 47, whereas the head 31^a of the screw is elongated to extend it to the right into the path of the line spacing pawl and constitutes a stop therefor, as shown in Figs. 1 and 2. From the last mentioned figure it will be 35 understood that under all adjustments of the member 30 the last portion of the stroke of the pawl 21 will bring the upper inclined face or edge 21^b thereof against the head or stop 31^a.

40 It has been hereinbefore explained that operating motion is transmitted from the handle 9 to the slide 20 and the pawl 21 through the spring 29. When, however, the pawl engages the stop 31^a as above explained this will arrest the pawl and slide, but the lost motion connection 18-19 will permit the handle to receive a continued movement against the plunger 28 and the resistance of its spring 29. This movement 45 will continue a short distance until the plunger is forced into the bore, as shown in Fig. 2, and the post or pin 17 engages the heel of the pawl 21 above its pivot 25, when further movement of the handle and 50 the parts controlled thereby is arrested. This is the condition of the parts as they appear in Fig. 2, and it results in, at this time, providing a positive train of connections between the line spacing handle and 55 pawl which firmly holds the latter against the stop 31^a and in interlocking engagement with the teeth of the line spacing wheel, to positively prevent overthrow of the latter and the platen connected therewith. When 60 pressure on the handle is released by the op-

erator the spring 14 will return the line spacing handle to normal position, and as the parts recede from the stop 31^a the spring 29 will cause pawl 21, slide 20, and handle 9 to assume their normal relation, one to another.

During the line spacing operation the post 17 will turn to present different faces for co-operation with the pin 28 through which motion is transmitted to the pawl and slide 20. However, the cylindrical contact surface of the post causes it to co-act effectively with the pin at all parts of the stroke and to maintain the pin 33 pressed down on the device 30, as well as to bring about 80 an effective engagement between the post and pawl at the last part of the stroke.

By providing a substantially straight inclined supporting edge or surface 34 on the regulating device 30 for the pawl to ride on, 85 said pawl does not have any change in the direction of its motion until it reaches and engages a tooth of the line spacing wheel. There is, therefore, every assurance that the pawl will engage the proper tooth of the wheel at all times and under all settings of the regulating device and conditions of use. The construction is such, moreover, that various parts of the line spacing mechanism are held against unrestrained loose play at all 90 times under the reaction of springs and there is therefore no unrestrained loosely moving parts to clatter and produce noise as the result of any such clatter in the operation of the machine. The operation of the line spacing mechanism is easy and smooth and results in the production of but comparatively little noise.

It will be observed that all parts of line spacing mechanism, except the wheel 3 and detent 8, are carried by the bracket 5 and may be introduced therewith or removed from the machine as a single unit; that a sweeping movement of the line spacing handle from left to right is effective by a single operation to line space the platen and return the carriage to the right to begin a new line of writing; and that the construction is simple, easy to adjust, comparatively inexpensive to manufacture and highly efficient in use.

Various changes in the construction may be made, and parts thereof employed without others, without departing from my invention as it is defined in the accompanying claims.

What I claim as new and desire to secure by Letters Patent is:

1. In a line space mechanism for typewriting or like machines, the combination of 125 a line spacing pawl, an adjustable spring-pressed line spacing regulating device on which the pawl normally rests and on which it has a sliding movement in its line spacing operation, and a separate hand controlled 130

- member co-acting with said regulating device to control its adjustment and thus determine the extent of line space, the regulating device co-acting with said separate hand controlled member to operate as a spring detent to hold it against accidental displacement from any of the line space determining positions to which it may be adjusted.
5. In a typewriting or like machine, the combination of a line spacing wheel, a pivoted line spacing pawl that extends longitudinally in one direction from its pivot, an overlapping pivoted line space regulating arm that extends from its pivot in the opposite direction and on which the pawl slides in its line spacing movement, and hand controlled means for adjusting said regulating arm to different set positions around its pivot and thereby determine the extent of line spacing.
6. In a typewriting or like machine, the combination of a line spacing wheel, a pivoted line spacing pawl that extends from its pivot in one direction, a pivoted line space regulating device that extends from its pivot in the opposite direction and on which the pawl slides, means for adjusting said regulating device to different set positions around its pivot to determine the extent of line spacing, and an extension of the pivot of said regulating device interposed in the path of the pawl under all adjustments of the regulating device to limit the throw of the pawl and hold it in interlocking engagement with the line spacing wheel and prevent overthrow thereof.
7. In a line space mechanism for typewriting or like machines, the combination of a line spacing wheel, a line spacing pawl, a spring pressed pivoted line space regulating device on which the pawl normally rests and has a sliding movement in its line spacing operation, the position of the regulating device in turning on its pivot determining the point in the throw of the pawl where it engages the line spacing wheel, and a separate hand controlled member co-acting with said regulating device to control its pivotal movement and thus determine the extent of line space, the regulating device co-acting with said hand controlled member to operate as a spring detent to hold it against accidental displacement from any of the line space determining positions to which it may be adjusted.
8. In a line space mechanism for typewriting or like machines, the combination of a line spacing pawl, an adjustable spring-pressed line spacing regulating device on which the pawl normally rests and has a sliding movement in its line spacing operation, a separate hand-controlled member co-acting with said regulating device to control its adjustment, a pin, and a series of pin-engaging notches between said regulating device and hand controlled member, whereby an adjustment of the hand controlled member will adjust the regulating device to dif-
1. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, and a separate hand controlled member co-acting with said regulating device to control its pivotal movement and thus determine the extent of line space, the regulating device co-acting with said hand controlled member to operate as a spring detent to hold it against accidental displacement from any of the line space determining positions to which it may be adjusted, and indices on said hand controlled member which co-act with a part of the line spacing pawl to indicate any of the adjusted positions to which the hand controlled member and regulating device may be set.
2. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, and a separate hand controlled member pivoted to turn in an arc at an angle to the arc through which the pivoted regulating device turns and co-acting with said regulating device to control its pivotal adjustment, the regulating device co-acting with said hand controlled member to operate as a spring detent to hold it against accidental displacement from any of the line space determining positions to which it may be adjusted.
3. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, and a separate hand controlled member co-acting with said regulating device to control its adjustment and thus determine the extent of line space, the regulating device co-acting with said hand controlled member to operate as a spring detent to hold it against accidental displacement from any of the line space determining positions to which it may be adjusted.
4. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, and a separate hand controlled member pivoted to turn in an arc at an angle to the arc through which the pivoted regulating device turns and co-acting with said regulating device to control its pivotal adjustment, the regulating device co-acting with said hand controlled member to operate as a spring detent to hold it against accidental displacement from any of the line space determining positions to which it may be adjusted.

ferent line determining positions and the regulating device will act as a spring detent to hold the hand controlled member against accidental displacement from the line determining position to which it may be adjusted, and indices on said hand controlled member which co-act with a part of the line spacing pawl to indicate any of the adjusted positions to which the hand controlled member and regulating device may be set and according to which of the pin-engaging notches said pin is seated in.

9. In a typewriting or like machine, the combination of a carriage bodily case shiftable as a whole, a line spacing lever, a line spacing pawl actuated thereby, an adjustable line space regulating guard or shield co-acting with said pawl and on which said pawl slides in its line spacing movement, and a bracket detachably mounted on and shiftable with the bodily shiftable carriage and on which all of said parts are mounted and with which they are detachable as a single unit.

10. In a typewriting or like machine, the combination of a carriage bodily case shiftable as a whole, a detachably mounted supporting bracket mounted on and shiftable with the bodily shiftable carriage, a line spacing lever pivoted on top of said bracket to swing horizontally from left to right, an off-set arm on said lever, a slide that moves fore-and-aft of the machine on top of said bracket and to which said off-set arm is pivotally connected to actuate it, a line spacing pawl pivoted on said slide, and an adjustable line space regulating guard or shield carried by the bracket and on which said pawl slides in its operating movement, all of said parts being mounted on the bracket and detachable therewith as a single unit.

11. In a line space mechanism for typewriting or like machines, the combination of a line spacing pawl, an adjustable spring-pressed line space regulating device on which the pawl normally rests and has a sliding movement in its line spacing operation, a separate hand controlled member co-acting with said regulating device to control its adjustment, and thus determine the extent of line space, the regulating device co-acting with said hand controlled member to operate as a spring detent to hold it against accidental displacement from any of the line space determining positions to which it may be adjusted, and a detachable bracket on which all of said parts are carried and with which they are detachable as a single unit.

12. In a line space mechanism for typewriting or like machines, the combination of a line spacing pawl, an adjustable spring-pressed line space regulating device on which the pawl normally rests and has a

sliding movement in its line spacing operation, a separate hand controlled member co-acting with said regulating device to control its adjustment, a pin, and a series of pin-engaging notches between said regulating device and hand controlled member, whereby an adjustment of the hand controlled member will adjust the regulating device to different line determining positions and the regulating device will act as a spring detent to hold the hand controlled member against accidental displacement from the line determining position to which it may be adjusted, and a detachable bracket on which all of said parts are carried and with which they are detachable as a single unit.

13. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, a separate hand controlled member co-acting with said regulating device to control its pivotal movement and thus determine the extent of line space, the regulating device co-acting with said hand controlled member to operate as a spring detent to hold it against accidental displacement from any of the line space determining positions to which it may be adjusted, and a detachable bracket on which all of said parts except the line spacing wheel are carried and with which they are detachable as a single unit.

14. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, a separate hand controlled member pivoted to turn in an arc at an angle to the arc through which the pivoted regulating device turns and co-acting with said regulating device to control its pivotal adjustment, the regulating device co-acting with said hand controlled member to operate as a spring detent to hold it against accidental displacement from the line space determining positions to which it may be adjusted, and a detachable bracket on which all of said parts except the line spacing wheel are carried and with which they are detachable as a single unit.

15. In a typewriting machine, the com-

bination of a line spacing wheel, a pivoted spacing pawl that extends from its pivot in one direction, a pivoted line space regulating device that extends from its pivot in the opposite direction and on which the pawl slides, means for adjusting said regulating device to different set positions around its pivot to determine the extent of line spacing, an extension of the pivot of said regulating device interposed in the path of the pawl under all adjustments of the regulating device to limit the throw of the pawl and hold it in interlocking engagement with the line spacing wheel and prevent overthrow thereof, and a detachable bracket on which all of said parts except the escapement wheel are carried and with which they are detachable as a single unit.

16. In a line space mechanism for typewriting or like machines, the combination of a line spacing pawl, an adjustable spring-pressed line space regulating device on which the pawl normally rests and has a sliding movement in its line spacing operation, a separate hand controlled member co-acting with said regulating device to control its adjustment and thus determine the extent of line space, the regulating device co-acting with said hand controlled member to operate as a spring detent to hold it against accidental displacement from any of the line space determining positions to which it may be adjusted, indices on said hand controlled member which co-act with a part of the line spacing pawl to indicate any of the adjusted positions to which the hand controlled member and regulating device may be set, and a detachable bracket on which all of said parts are carried and with which they are detachable as a single unit.

17. In a line space mechanism for typewriting or like machines, the combination of a line spacing pawl, an adjustable spring-pressed line space regulating device on which the pawl normally rests and has a sliding movement in its line spacing operation, a separate hand-controlled member co-acting with said regulating device to control its adjustment, a pin, and a series of pin-engaging notches between said regulating device and hand controlled member whereby an adjustment of the hand controlled member will adjust the regulating device to different line determining positions and the regulating device will act as a spring detent to hold the hand controlled member against accidental displacement from the line determining position to which it may be adjusted, indices on said hand controlled member which co-act with a part of the line spacing pawl to indicate any of the adjusted positions to which the hand controlled member and regulating device may be set and according to which of

the pin-engaging notches said pin is seated in, and a detachable bracket on which all of said parts are carried and with which they are detachable as a single unit.

18. In a typewriting or like machine, the combination of a slide, a pawl pivoted on said slide to move therewith as well as to turn on its pivot, a line space regulating device on which said pawl slides and which determines the extent of line space movement effected by said pawl, a line spacing lever connected to said slide, and a spring interposed between said pawl and lever and which exerts its force to turn the pawl on its pivot and maintain it in sliding engagement with said regulating device during the throw of the pawl.

19. In a typewriting or like machine, the combination of a slide, a pawl mounted on said slide for bodily movement therewith as well as for an independent pivotal movement thereon, a line space regulating guard or shield on which said pawl slides and which determines the extent of line space movement effected by said pawl, a line spacing lever, and a spring interposed between said pawl and lever and which exerts its force to turn the pawl on its pivot and maintain it in sliding engagement with said regulating device during the throw of the pawl and through which motion is transmitted from said lever to said slide.

20. In a typewriting or like machine, the combination of a line spacing wheel; a line spacing pawl; a stop to limit the throw of the pawl and hold it in engagement with the line spacing wheel and prevent overthrow of the latter; a line spacing lever; and operative connections between said pawl and lever including a spring, and means by which the force of said spring is overcome at the last portion of the line spacing operation and said lever positively engages the pawl to hold it engaged with said stop and wheel.

21. In a typewriting or like machine, the combination of a line spacing wheel, a slide, a line spacing pawl pivoted on said slide, a line spacing lever, a lost motion connection between said slide and lever, a stop for limiting the throw of said pawl and for holding it in engagement with the line spacing wheel in order to prevent an overthrow of the latter, and a spring interposed between said pawl and lever and the force of which is overcome after the pawl is arrested by said stop when the lost motion connection enables the lever to be brought into positive engagement with the pawl to hold it engaged with the stop and wheel.

22. In a typewriting or like machine, the combination of a line spacing wheel, a slide, a line spacing pawl pivoted on said slide, an adjustable line space regulating device on which said pawl slides and which deter-

mines the extent of line space movement, a line spacing lever, a lost motion connection between said slide and lever, a stop for limiting the throw of said pawl and for holding it in engagement with the line spacing wheel in order to prevent an overthrow of the latter, and a spring interposed between said pawl and lever for holding the pawl against said regulating device and the force of which spring is overcome after the pawl is arrested by said stop when the lost motion connection enables the lever to be brought into positive engagement with the pawl to hold it engaged with the stop and wheel.

23. In a typewriting machine, the combination of a line spacing wheel, a slide, a line spacing pawl pivoted on said slide to move bodily therewith and to receive a pivotal movement thereon, a line spacing lever, a lost motion connection between said slide and lever, a stop for limiting the throw of said pawl and for holding it in engagement with said wheel and preventing an over-throw of the latter, a spring-pressed plunger carried by said pawl, and a pin on said line spacing lever against which said plunger bears, whereby the lost motion connection will enable the lever to receive a final movement against the force of the spring-pressed plunger after the pawl is arrested by said stop and such final movement of the lever is effective to bring the said pin thereon into positive engagement with the pawl and prevent its disengagement from the line spacing wheel and stop.

24. In a typewriting machine, the combination of a line spacing wheel, a slide, a line spacing pawl pivoted on said slide to move bodily therewith and to receive a pivotal movement thereon, an adjustable line space regulating device on which said pawl slides and which determines the extent of line space movement, a line spacing lever, a lost motion connection between said slide and lever, a stop for limiting the throw of said pawl and for holding it in engagement with said wheel and preventing an overthrow of the latter, a spring-pressed plunger carried by said pawl, and a pin on said line spacing lever against which said plunger bears for holding the pawl against said regulating device whereby the lost motion connection will enable the lever to receive a final movement against the force of the spring-pressed plunger after the pawl is arrested by said stop and such final movement of the lever is effective to bring the said pin thereon into positive engagement with the pawl and prevent its disengagement from the line spacing wheel and stop.

25. In a typewriting or like machine, the combination of a substantially horizontally disposed line spacing lever movable from left to right to line space the platen and return the carriage and having an off-set arm, a slide that moves fore-and-aft of the machine, an operative connection between said off-set arm on the lever and said slide, a line spacing pawl pivoted on said slide and extending rearwardly from its pivot, a pivoted substantially horizontally disposed line space regulating arm that extends forward from its pivot and overlaps said pawl and on which said pawl rides in its line spacing movement, a spring which tends to move said arm down around its pivot, and a hand-controlled substantially vertically disposed pivoted adjusting member co-operative with said regulating device to adjust it around its pivot to different set positions, the regulating device acting as a spring-pressed detent on said adjusting member to hold it in adjusted position.

26. In a typewriting or like machine, the combination of a substantially horizontally disposed line spacing lever movable from left to right to line space the platen and return the carriage and having an off-set arm, a slide that moves fore-and-aft of the machine, an operative connection between said off-set arm on the lever and said slide, a line spacing pawl pivoted on said slide and extending rearwardly from its pivot, a pivoted substantially horizontally disposed line space regulating arm that extends forward from its pivot and overlaps said pawl and on which said pawl rides in its line spacing movement, a spring which tends to move said arm down around its pivot, a hand-controlled substantially vertically disposed pivoted adjusting member co-operative with said regulating device to adjust it around its pivot to different set positions, the regulating device acting as a spring-pressed detent on said adjusting member to hold it in adjusted position.

27. In a typewriting or like machine, the combination of a substantially horizontally disposed line spacing lever movable from left to right to line space the platen and return the carriage and having an off-set arm, a slide that moves fore-and-aft of the machine, an operative connection between said off-set arm on the lever and said slide, a line spacing pawl pivoted on said slide and extending rearwardly from its pivot, a pivoted substantially horizontally disposed line space regulating arm that extends forward from its pivot and overlaps said pawl and on which said pawl rides in its line spacing movement, a spring which tends to move said arm down around its pivot, a hand-controlled substantially vertically disposed pivoted adjusting member co-operative with said regulating device to adjust it around its pivot to different set positions, the regulating device acting as a spring-pressed detent on said adjusting member to hold it in adjusted position, and indices on said adjusting device which co-act with a part of the line spacing pawl to indicate the different line determining positions to which said adjusting member and regulating device are adjusted.

its pivot to different set positions, the regulating device acting as a spring-pressed detent on said adjusting member to hold it in adjusted position, and a detachable bracket on which all of said parts are carried and with which they may be attached or detached as a single unit.

28. In a typewriting or like machine, the combination of a substantially horizontally disposed line spacing lever movable from left to right to line space the platen and return the carriage and having an off-set arm, a slide that moves fore-and-aft of the machine, a lost motion connection between said off-set arm on the lever and said slide, a line spacing pawl pivoted on said slide and extending rearwardly from its pivot, a pivoted substantially horizontally disposed line space regulating arm that extends forward from its pivot and overlaps said pawl and on which said pawl rides in its line spacing movement, a spring which tends to move said arm down around its pivot, a hand-controlled substantially vertically disposed pivoted adjusting member co-operative with said regulating device to adjust it around its pivot to different set positions, the regulating device acting as a spring-pressed detent on said adjusting member to hold it in adjusted position, a stop for limiting the throw of the pawl and for holding it in interlocking engagement with the line spacing wheel in order to prevent overthrow of the latter, and a spring-pressed plunger intermediate the line spacing lever and pawl for holding the latter on said regulating arm during the sliding movement of the pawl thereon, the construction and arrangement of the parts being such that a final movement of the line spacing handle after the pawl engages said stop will by reason of said lost motion connection enable said lever to force the plunger against the power of its spring and bring the lever in positive engagement with the pawl and hold the pawl against said stop and in engagement with the line spacing wheel.

29. In a typewriting or like machine, the combination of a substantially horizontally disposed line spacing lever movable from left to right to line space the platen and return the carriage and having an off-set arm, a slide that moves fore-and-aft of the machine, lost motion connection between said off-set arm on the lever and said slide, a line spacing pawl pivoted on said slide and extending rearwardly from its pivot, a pivoted substantially horizontally disposed line space regulating arm that extends forward from its pivot and overlaps said pawl and on which said pawl rides in its line spacing movement, a spring which tends to move said arm down around its pivot, a hand-controlled substantially vertically disposed pivoted adjusting member co-operative with

said regulating device to adjust it around its pivot to different set positions, the regulating device acting as a spring-pressed detent on said adjusting member to hold it in adjusted position, a stop for limiting the throw of the pawl and for holding it in interlocking engagement with the line spacing wheel in order to prevent overthrow of the latter, a spring-pressed plunger intermediate the line spacing lever and pawl for holding the latter on said regulating arm during the sliding movement of the pawl thereon, the construction and arrangement of the parts being such that a final movement of the line spacing handle after the pawl engages said stop will by reason of said lost motion connection enable said lever to force the plunger against the power of its spring and bring the lever in positive engagement with the pawl and hold the pawl against said stop and in engagement with the line spacing wheel, and a detachable bracket on which all of said parts are carried and with which they may be attached or detached as a single unit.

30. In a typewriting or like machine, the combination of a line spacing wheel, a line spacing lever mounted on a vertical axis to swing from left to right, a detachable bracket on which said lever is pivoted, a slide mounted on said bracket and having a pin and slot connection therewith, a line spacing pawl carried by and pivoted on said slide, a locking pin carried by said bracket and with which the pawl co-acts at the end of its line spacing movement to hold the pawl in engagement with the line spacing wheel and prevent an overthrow of the latter, and a pin-and-slot connection between said line spacing lever and slide that enables the lever to continue its operating movement after the slide is arrested and thus bring the lever into positive engagement with the pawl and hold it in engagement with said locking pin.

31. In a typewriting or like machine, the combination of a line spacing wheel, a line spacing lever mounted on a vertical axis to swing from left to right, a detachable bracket on which said lever is pivoted, a slide mounted on said bracket and having a pin-and-slot connection therewith, a line spacing pawl carried by and pivoted on said slide, a locking pin carried by said bracket and with which the pawl co-acts at the end of its line spacing movement to hold the pawl in engagement with the line spacing wheel and prevent an overthrow of the latter, a cylindrical post carried by said line spacing lever, a spring pressed plunger carried by said pawl and co-operative with said post, an adjustable line space regulating device on which the pawl slides and against which it is pressed by said spring-pressed plunger, and a pin-and-slot connection between said

line spacing lever and slide that enables the lever to continue its operating movement after the slide is arrested and press said plunger against its spring and bring said post into positive engagement with the pawl and hold it in engagement with said locking pin.

32. In a typewriting machine, the combination of a line spacing wheel, a line spacing lever mounted on a vertical axis to swing from left to right, a detachable bracket on which said lever is pivoted, a slide mounted on said bracket and having a pin-and-slot connection therewith, a line spacing pawl carried by and pivoted on said slide, a locking pin carried by said bracket and with which the pawl co-acts at the end of its line spacing movement to hold the pawl in engagement with the line spacing wheel and prevent an overthrow of the latter, a cylindrical post carried by said line spacing lever, a spring-pressed plunger carried by said pawl and co-operative with said post, an adjustable spring-pressed line space regulating device on which the pawl slides and against which it is pressed by said spring-pressed plunger, a separate and distinct hand-controlled adjusting member co-acting with said regulating device to adjust it and against which the regulating device bears and acts as a spring detent to hold the ad-

justing device in its adjusted position, and a pin-and-slot connection between said line spacing lever and slide that enables the lever to continue its operating movement after the slide is arrested and press said plunger against its spring and bring said post into positive engagement with the pawl and hold it in engagement with said locking pin, all of said parts except the line spacing wheel being carried by said bracket and attachable and detachable therewith as a single unit.

33. In a typewriting machine, the combination of a line space lever, a pivoted spring-pressed line space pawl, a line space wheel, a pivoted line space regulator having an inclined edge along which a pin on the pawl is adapted to slide and having also a set of notches of varying depth beneath said inclined edge, a hand controlled lever provided with a pin to engage said notches one at a time and hold said regulator and inclined edge thereof at varying elevations, and a spring for holding said line space regulator firmly on said pin and thus firmly holding the hand controlled lever against accidental displacement.

Signed at Middletown, in the county of Middlesex, and State of Connecticut this 11th day of March, A. D. 1925.

GEORGE GOULD GOING.
